[57] **CLAIM**

The ornamental design for a combination handset telephone, its stand, and a carrier case therefor, as shown and described.

DESCRIPTION

FIGS. 1 and 2 are respectively front and rear elevational views of the handset telephone and its stand showing them in cradled relationship separately from the carrier case for clarity of illustration;

FIGS. 3 and 4 are respectively right and left elevational views of the FIGS. 1 and 2 portrayal;

FIGS. 5 and 6 are respectively top and bottom plan views of the FIGS. 1 and 2 portrayal;

FIG. 7 is a sectional view taken along line VII—VII in FIG. 1 with interior construction omitted;

FIG. 8 is a left side, top and front perspective view of the FIGS. 1 and 2 portrayal; and,

FIG. 9 is a rear, top and left side perspective view of the carrier case in opened condition with its cover pulled aside to show the handset telephone and stand contained therewithin.

The showing of the carrier case's handle strap in fragmentary form in FIG. 9 is for ease of illustration and clarity of presentation. That part of the carrier case cover not visible is plain and unadorned.
